UNITED STATES PATENT OFFICE.

BERG HEINRICH, OF ANDERSON, INDIANA, ASSIGNOR TO MID-WEST BOX COMPANY,
OF ANDERSON, INDIANA, A CORPORATION OF INDIANA.

MACHINE FOR MAKING CORRUGATED BOARD.

1,188,650.

Specification of Letters Patent. Patented June 27, 1916.

Application filed January 20, 1915. Serial No. 3,196.

To all whom it may concern:

Be it known that I, BERG HEINRICH, a resident of Anderson, in the county of Madison and State of Indiana, have invented certain new and useful Improvements in Machines for Making Corrugated Board, of which the following is a full, clear, and exact description.

The invention relates to machines for making corrugated board and more particularly to mechanism for cutting a continuous web into sheets of the desired size.

One object of the invention is to provide improved cutting mechanism which dispenses with the necessity of providing variable speed-gearing for operating it.

Another object of the invention is to provide mechanism which comprises cutters traveling synchronously with the web so that there will be no retarding effect upon the web and so that stiff corrugated board may be cut without buckling the web.

A further object is to provide improved cutting mechanism which is adjustable to vary the length of the cut and is efficient in use.

The invention consists in the several novel features hereinafter set forth and more particularly defined by claims at the conclusion hereof.

In the drawings: Figure 1 is a side elevation of a portion of a corrugated board machine embodying the invention. Fig. 2 is a plan. Fig. 2^a is a section taken on line 2^a-2^a of Fig. 1. Fig. 2^b is a detail of one end of the rotatable cutter-head and its operating lever. Fig. 3 is a side elevation of the cutting mechanism, the parts being shown in position assumed during the outstroke of the cutter carriage and before the sheet has been severed from the web. Fig. 4 is a similar view, showing the parts in position assumed, during the outstroke of the carriage, after the sheet has been severed from the web. Fig. 4^a is a detail section taken on line 4^a-4^a of Fig. 3. Fig. 5 is a central vertical section of the cutter, showing the parts in position corresponding to that shown in Fig. 3. Fig. 6 is a similar view, showing the parts in position corresponding to that shown in Fig. 4. Fig. 6^a is a detail section of the joint between the members of the shock-absorbing linkage for the cutter-carriage.

55 The improved cutting-mechanism is exem-

plified in a machine for making double faced board which comprises a pair of suitable endless conveyers 10 and 11 between which the web, after it has been faced, is fed forwardly continuously and heated to cause 60 the agglutinant for the second facing to set and to finish the board. In practice, it is customary to heat the web as it is fed by the conveyers, but since this mechanism forms no special feature of the present invention, it has not been illustrated. The delivery end of the upper conveyer 10 passes around sprockets 12 on a shaft 14, which is mounted on a suitable frame 15 and the lower endless conveyer 11 passes around 70 sprockets 16 on a shaft 17, which is also mounted on said frame. These conveyers are adapted to be continuously driven by a power-pulley 18 which is loose on a shaft 19; and a suitable clutch 20 drives shaft 19 from 75 said power wheel, while pinion 21 fixed on shaft 19 meshes with gear-wheel 22 which is fixed on the shaft 17, on which shaft 17 is also fixed a gear 23 which meshes with a gear 24 on shaft 14 to drive the upper conveyer 10. This mechanism is adapted to continuously feed or advance the finished web to the cutting mechanism.

The cutting mechanism is designed to separate sheets from the web during the continuous advance of the web in one direction and comprises a rotary cutter-head 27 to which is secured a knife or blade 28. This cutter-head is provided with end-spindles 29, 30 which are journaled in bearings 31, respectively, on a reciprocable carriage 32. A vertically disposed knife 33, co-acting with the rotary knife 28, to sever a sheet from the web, is fixed to the end of the carriage. This carriage is reciprocably 90 sustained upon members 15^a of the frame 15 by rollers 33^a which ride on said members respectively and a shaft 34 which is journaled in the carriage and has gears 35 therein which mesh with and are adapted 95 to travel in racks 36, which are fixed to said frame-members. These rack and gear connections between the cutter carriage and the frame support one end of the frame and insure a strictly parallel movement of the 100 carriage in the direction of travel of the web.

Intermittent reciprocating movement is imparted to the cutter-carriage to cause the cutter-blade to travel in unison synchro- 110

2

nously with the web, and rotary movement is imparted to the cutter-head 27 to sever a sheet from the web while the cutter-members are both advancing synchronously with the web and also to retract or rotate the cutter-head to permit the web to pass beneath the cutter head before the cutter-carriage has completed its outstroke so as to avoid buckling or bending of the web.

10 The mechanism for imparting intermittent reciprocatory movement to the cutter carriage comprises a beveled gear-wheel 37 which is fixed to the constantly rotating shaft 17 and meshes with a beveled gear 38 on a longitudinal shaft 39 which is suitably journaled in bearings on the frame and continuously drives a gear-wheel 40 fixed to the inner end thereof. This gear wheel 40 meshes with a pair of oppositely disposed gears 41 and 42 both of which are loose upon a shaft 43 and are constantly driven in opposite directions by gear 40. A clutch-member 44 is slidably mounted on shaft 43 and is splined to the shaft so that when 20 the clutch-member rotates in either direction, said shaft will be correspondingly driven. The ends of member 44 are provided with clutch-teeth adapted to mesh with corresponding teeth on the wheels 41, 42, respectively, so that shaft 43 may be driven in either direction according to the position of clutch-member 44. This clutch member may also assume a neutral position as shown in Fig. 2, when the cutter mechanism is to remain inoperative.

30 A gear-wheel 45 is secured to the inner end of shaft 43 and meshes with a rack 46 fixed to a reciprocable cutter-operating bar 47. The inner end of this bar is suitably mounted in a guide (not shown) on frame 15 and the outer end is held vertically by the spindle 30 on the cutter head 27. A parallel bar 49 is secured in spaced relation and beneath bar 47 to form a slot or guideway 50 for the spindle 30. Bars 47 and 49 are secured together in spaced relation by blocks 51 and 52 which are bolted to said bars. Block 52 serves as an abutment for engaging spindle 30 of the cutter-head to shift the head and parts carried thereby inwardly. A block 53, which is adjustably secured to and between bars 47, 49 by a bolt 54 and plate 54a, serves as an abutment for shifting the spindle 30 and cutter-carriage outwardly. The slot or guide 50 permits the desired lost-motion between operating bar 47 and the cutter-head, so that the latter may remain stationary while any desired portion of the web is being fed outwardly and until it is necessary to operate the cutter-carriage.

40 Mechanism is provided for automatically shifting clutch-member 44 to cause it to be alternately shifted into operative relation with gears 41 and 42 so that gear 45, which

meshes with rack 46 will be intermittently shifted in opposite directions to reciprocate the cutter-operating bar 47. This mechanism comprises a clutch-controlling lever 56 which is pivoted to the frame at 57 and is provided with an arm 58 carrying studs 59 extending into an annular groove on clutch 44. The inner end of this clutch-lever carries a rod 60 which is slidable therein and coil springs 61 and 62 are placed on this rod and between the headed ends thereof and opposite sides of the lever 56. An abutment 63, in the form of an adjustable screw, is adapted to strike one end of rod 60 to yielding shift, by means of spring 62, clutch-member 56 into engagement with gear 42 to operate the cutter-operating bar 47 outwardly and a block 64, which is adjustably secured to bar 47, is adapted to strike the other end of rod 60 to shift clutch-lever 56 into position to mesh with gear 41 to operate bar 47 inwardly after each outstroke. Springs 61 and 62 provide for the yielding movement of the lever responsive to the abutment 63 and 64 to avoid breakage of the clutch teeth.

50 Assuming the cutter mechanism to be in position indicated in Fig. 1 and the clutch lever 56 to be in position to cause the clutch-member 44 to be driven by gear 41, bar 47 will be operated inwardly and toward the end of the instroke, abutment 52 will engage spindle 30 and retract the cutter carriage, the latter moving in synchronism with the bar 47. At the conclusion of the instroke, 100 abutment 63 will shift clutch-lever 56 to cause shaft 43 to be driven by gear 42 so that bar 47 will be shifted outwardly in synchronism with the web. During the outstroke, the cutter carriage will remain stationary until abutment 53 engages spindle 30 and during the remainder of the outstroke, the cutter-carriage will move in synchronism with the web as a result of the engagement of abutment 53 with the spindle. 105 During this operation of the outstroke, the cutter head will be rotated to sever the sheet from the web. Mechanism for effecting this rotary movement of the cutter-head comprises a lever 66 which is affixed to the spindle 110 30 of the rotary cutter-head and carries a spring-pressed dog 67 at its upper end, and an abutment 68 which is stationary and secured to the frame 15. Dog 67 is pivoted to lever 66 at 69 and is normally held to 115 engage the stop 70 on the lever by a spring 71. During the instroke of the carriage, the upper end of dog 67 will ride under abutment 68, the spring permitting the dog to yield for this purpose. During the outstroke of the carriage, dog 67 will be detained by abutment 68, causing the spindle 120 30 of the cutter-head to be rotated as the carriage is moving outwardly until the dog is free to pass under the abutment 68. This 125

rotation of the cutter-head will cause knife 28 to sever a sheet from the web while the carriage is moving in synchronism with the web. After the web has been severed and before the carriage reaches the end of its outstroke, dog 67 will have passed beneath and clear of abutment 68 and thereupon an abutment 72 fixed to the lower arm of lever 66 will strike a stop 73 in the form of an adjustable screw, which is held on the frame 15 to cause the lever to be reversely rotated while the carriage is still moving in synchronism with the web and until the lower end of the lever 66 engages a stop 74 depending 20 from the carriage. Thereupon, the cutter-head will be rotated into position to permit the web to pass under it while the cutter-carriage is stationary and during the retraction of the cutter-carriage. Obviously, by 25 adjustment of abutment 53, the time elapsing between the cutting operations of knife 28, the length of the sheet severed from the web and the number of reciprocations may be readily varied so as to cut a web into 30 sheets of different lengths.

The end of spindle 30 is squared, as at 30^a for the application of a crank to operate the cutter manually. In practice, it sometimes occurs that a defective portion is to 35 be cut from the web and by operating the cutter-head 27 manually this can be readily done, because of the lost motion connection between the cutter-operating bar and the spindles 30. Obviously, clutch-lever 56 may 40 be manually shifted to bring the clutch-member 44 to its neutral position or into engagement with either of the gears 41, 42, when desired in practice in starting the machine.

45 In order to avoid shocking stresses upon the cutter-carriage at the end of its reciprocating movement, shock-absorbing linkages are provided between the supporting frame and the cutter-carriage, one of these linkages being disposed adjacent each side of the machine. Each of these linkages consists of a link 90 which is pivoted to the frame, as at 91, and a link 92, which is pivoted to the cutter-carriage at 93 and to 50 the link 90 by a bolt 94. A spider washer 95, having spring arms, is interposed between the bolt and one of the links to frictionally press the links together. As a result, the links will be frictionally pressed 55 together to cushion the movement of the carriage and absorb the shock at the end of the movements of the carriage. The cutting-mechanism will operate intermittently to successively cut the web without attention upon the part of the operator, because the reciprocations of the cutter-operating bar are automatically shifted by the abutments and the clutch.

60 The invention thus exemplifies an improved cutter-mechanism for corrugated

board machines in which the cutter-carriage is operated during the cutting operation in synchronism with the web, which is adjustable to vary the length of the cut without the use of variable speed-gearing for driving 65 the cutter-mechanism. The lost motion connection between the operating mechanism and the cutter-carriage makes it possible to employ a short reciprocatory stroke, during which the carriage will move synchronously with the web and also permits ready 70 adjustment for varying the length of the cut from the web. The cutting-mechanism is simple in construction and efficient in 75 operation.

80 The invention is not to be understood as restricted to the details set forth, since these may be modified within the scope of the appended claims, without departing from the spirit and scope of the invention.

85 Having thus described the invention, what I claim as new and desire to secure by Letters Patent, is:

1. In a machine of the character described, the combination of mechanism for 90 continuously feeding a web, a carriage mounted to move bodily in a straight plane parallel to the travel of the web, cutters mounted on said carriage, one of which is rotatably mounted on the carriage, mechanism for reciprocating the carriage and mechanism for operating the rotatable cutter to sever the web while it is moving longitudinally with the web in one direction.

95 2. In a machine of the character described, the combination of mechanism for continuously feeding a web, a carriage mounted to move bodily in a straight plane parallel to the web, a pair of cutters mounted on said carriage, one of said cutters being rotatable, mechanism for positively shifting the reciprocable carriage in both directions, and mechanism for operating the rotatable cutter to sever the web while the carriage is 100 moving synchronously with the web.

105 3. In a machine of the character described, the combination of mechanism for continuously feeding a web, straight tracks extending in a plane parallel to the line of travel of the web, a carriage provided with rollers traveling on said tracks, cutters mounted on the carriage, one of the cutters being rotatable, mechanism for reciprocating the carriage, and mechanism for operating the cutter to sever the web while the carriage is 110 moving synchronously with the web in one direction.

115 4. In a machine of the character described, the combination of mechanism for continuously feeding a web, reciprocable cutter-mechanism mounted to move bodily in the line of the carriage, mechanism for reciprocating the cutter-mechanism synchronously with the web, a lost-motion connection between said reciprocating mechanism and the 120

- cutter mechanism, and mechanism for operating the cutter-mechanism to cut the web while moving with the web.
5. In a machine of the character described, the combination of mechanism for continuously feeding a web, a reciprocable carriage, mounted to move in the line of travel of the web, a cutter movably mounted on the carriage, mechanism for reciprocating the carriage synchronously with the web, a lost-motion connection between said reciprocating mechanism and the carriage, and mechanism for operating the cutter while the carriage is moving with the web.
- 10 6. In a machine of the character described, the combination of mechanism for continuously feeding a web, a reciprocable carriage, mounted to move in the line of travel of the web, a cutter pivotally mounted on the carriage, mechanism for reciprocating the carriage synchronously with the web, a lost-motion connection between said reciprocating mechanism and the carriage, and mechanism for operating the cutter while it is moving with the web.
- 15 7. In a machine of the character described, the combination of mechanism for continuously feeding a web, a reciprocable carriage movable in the line of travel of the web, a cutter movably mounted on the carriage, mechanism for reciprocating the carriage synchronously with the web, and mechanism for operating the cutter while the carriage is moving with the web, comprising a lever and an abutment for shifting the lever.
- 20 8. In a machine of the character described, the combination of mechanism for continuously feeding a web, a reciprocable carriage movable in the line of travel of the web, a cutter pivotally mounted on the carriage, mechanism for reciprocating the carriage synchronously with the web, and mechanism for rocking the cutter while the carriage is moving with the web, comprising a lever and an abutment for shifting the lever.
- 25 9. In a machine of the character described, the combination of mechanism for continuously feeding a web, a reciprocable carriage, movable in the line of travel of the web, a cutter movably mounted on the carriage, mechanism for shifting the carriage synchronously and longitudinally with the web, and mechanism for operating the cutter while the carriage is moving with the web, comprising a lever pivoted on the carriage and a stationary abutment for shifting the lever.
- 30 10. In a machine of the character described, the combination of mechanism for continuously feeding a web, a reciprocable carriage, movable in the line of travel of the web, a cutter movably mounted on the carriage, mechanism for reciprocating the carriage synchronously with the web, mechanism for operating the cutter while the carriage is moving with the web, comprising a lever, a stationary abutment and a dog, and a stop between the carriage and the lever for limiting the movement of the lever in one direction.
- 35 11. In a machine of the character described, the combination of mechanism for continuously feeding a web, a reciprocable carriage movable in the line of travel of the web, a cutter pivotally mounted on the carriage, mechanism for reciprocating the carriage synchronously with the web, and mechanism for rocking the cutter on the carriage, comprising a lever for shifting the cutter, and stationary abutments for alternately shifting the lever in opposite directions.
- 40 12. In a machine of the character described, the combination of mechanism for continuously feeding a web, a reciprocable carriage, movable in the line of travel of the web, a cutter movably mounted on the carriage, mechanism for reciprocating the carriage synchronously with the web, and mechanism for operating the cutter while the carriage is moving with the web, comprising a lever for shifting the cutter, and stationary abutments for alternately shifting the lever in opposite directions.
- 45 13. In a machine of the character described, the combination of mechanism for continuously feeding a web, a reciprocable carriage, movable in the line of travel of the web, a cutter movably mounted on the carriage, mechanism for reciprocating the carriage synchronously with the web, and mechanism for operating the cutter while the carriage is moving with the web, comprising a lever, and a stop between the carriage and the lever for limiting the movement of the lever in one direction.
- 50 14. In a machine of the character described, the combination of mechanism for continuously feeding a web, a reciprocable carriage, movable in the line of travel of the web, a cutter movably mounted on the carriage, mechanism for reciprocating the carriage synchronously with the web, and mechanism for operating the cutter while the carriage is moving with the web, comprising a lever and a stationary stop and a dog.
- 55 15. In a machine of the character described, the combination of mechanism for continuously feeding a web, a reciprocable carriage, movable in the line of travel of the web, a cutter movably mounted on the carriage, mechanism for reciprocating the carriage synchronously with the web, mechanism for operating the cutter while the carriage is moving with the web, comprising a lever, a stationary abutment and a dog, and a stop between the carriage and the lever for limiting the movement of the lever in one direction.

16. In a machine of the character described, the combination of mechanism for continuously feeding a web, bodily reciprocable cutter-mechanism, movable in the line of travel of the web, a connection for reciprocating the cutter-mechanism and mechanism for operating said connection, comprising reversible gearing, a clutch, and means for automatically shifting the clutch to alternately operate the connection in opposite directions.

17. In a machine of the character described, the combination of mechanism for continuously feeding a web, a reciprocable cutter carriage, movable in the line of travel of the web, a cutter on the carriage, a connection for reciprocating the carriage, mechanism for operating said connection comprising reversible gearing, a clutch and means for automatically shifting the clutch to alternately operate the connection in opposite directions, and means for operating the cutter on the carriage.

18. In a machine of the character described, the combination of mechanism for continuously feeding a web, a reciprocable cutter carriage, movable in the line of travel of the web, an adjustable connection for reciprocating the carriage, and mechanism for operating said connection, comprising reversible gearing, a clutch and means for automatically shifting the clutch to alternately operate the connection in opposite directions.

19. In a machine of the character described, the combination of mechanism for continuously feeding a web, a reciprocable cutter carriage, movable in the line of travel of the web, a connection for reciprocating the carriage, mechanism for reciprocating the connection comprising reversible gearing, and a clutch, and means on the connection for automatically shifting the clutch to cause the gearing to alternately drive the connection in opposite directions.

20. In a machine of the character described, the combination of mechanism for continuously feeding a web, a reciprocable cutter-carriage, movable in the line of travel of the web, an adjustable connection for reciprocating the carriage, mechanism for reciprocating the connection comprising reversible gearing, and a clutch, and means on the connection for automatically shifting the clutch to cause the gearing to alternately drive the connection in opposite directions.

21. In a machine of the character described, the combination of mechanism for continuously feeding a web, a reciprocable cutter carriage, movable in the line of travel of the web, a cutter pivoted on the carriage, a connection for reciprocating the carriage, mechanism for reciprocating the connection comprising a clutch and reversible gearing, means on the connection for automatically

shifting the clutch to cause the gearing to alternately drive the connection in opposite directions, and means controlled by the connection for rocking the cutter.

22. In a machine of the character described, the combination of mechanism for continuously feeding a web, a reciprocable carriage, movable in the line of travel of the web, a cutter movably mounted on the carriage, a reciprocable bar for operating the carriage synchronously with the web, mechanism for reciprocating said bar, and mechanism for operating the cutter relatively to the carriage while the carriage is moving with the web.

23. In a machine of the character described, the combination of mechanism for continuously feeding a web, a reciprocable carriage, movable in the line of travel of the web, a cutter movably mounted on the carriage, a reciprocable bar for operating the carriage synchronously with the web, a lost-motion connection between the bar and the carriage, mechanism for reciprocating said bar, and mechanism for operating the cutter relatively to the carriage while the carriage is moving with the web.

24. In a machine of the character described, the combination of mechanism for continuously feeding a web, a reciprocable carriage, movable in the line of travel of the web, a cutter pivoted on the carriage, a reciprocable bar for operating the carriage synchronously with the web, a lost-motion connection between the bar and the carriage, mechanism for reciprocating said bar and mechanism controlled by the movement of the carriage, for rocking the cutter while the carriage is moving with the web.

25. In a machine of the character described, the combination of mechanism for continuously feeding a web, a reciprocable carriage, movable in the line of travel of the web, a cutter movably mounted on the carriage, a reciprocable bar for operating the carriage synchronously and longitudinally with the web, abutments on the bar for shifting the carriage in opposite directions respectively, mechanism for reciprocating the bar, and mechanism for operating the cutter while the carriage is moving with the web.

26. In a machine of the character described, the combination of mechanism for continuously feeding a web, a reciprocable carriage, movable in the line of travel of the web, a cutter movably mounted on the carriage, a reciprocable bar for operating the carriage synchronously and longitudinally with the web, abutments on the bar for shifting the carriage in opposite directions, respectively, the abutments being spaced to permit the carriage to remain stationary during a part of each stroke of the bar, mechanism for reciprocating the bar,

and mechanism for operating the cutter while the carriage is moving with the web.

27. In a machine of the character described, the combination of mechanism for continuously feeding a web, a reciprocating carriage, movable in the line of travel of the web, a cutter movably mounted on the carriage, a reciprocable bar for operating the carriage synchronously and longitudinally with the web, abutments on the bar for shifting the carriage in opposite directions respectively, one of said abutments being adjustable, the abutments being spaced to permit the carriage to remain stationary during a part of each stroke of the bar, mechanism for reciprocating the bar, and mechanism for operating the cutter while the carriage is moving with the web.

28. In a machine of the character described, the combination of mechanism for continuously feeding a web, cutter-mechanism mounted to move bodily in the line of the travel of the web, mechanism for bodily reciprocating the cutter-mechanism for operating the cutter-mechanism to sever the web and frictional cushioning means for the cutter-mechanism.

29. In a machine of the character described, the combination of mechanism for continuously feeding a web, cutter-mech-

nism mounted to move bodily in the line of the travel of the web, mechanism for bodily reciprocating the cutter-mechanism, mechanism for operating the cutter-mechanism to sever the web, and a shock-absorbing linkage connected to the cutter-mechanism.

30. In a machine of the character described, the combination of mechanism for feeding the web, a reciprocable carriage mounted to move in the line of the travel of the web, a cutter movably mounted on the carriage, mechanism for reciprocating the carriage, mechanism for operating the cutter to cut a web and frictional cushioning means for the carriage.

31. In a machine of the character described, the combination of mechanism for continuously feeding a web, cutter-mechanism mounted to move bodily in the line of the travel of the web, mechanism for bodily reciprocating the cutter-mechanism, mechanism for operating the cutter-mechanism to sever the web, a linkage connected to the carriage and a friction-device applied to the linkage.
